UNITED STATES PATENT OFFICE.

GLENN V. GLADVILLE, OF BLOOMFIELD, INDIANA.

SILO HOOP.

Application filed February 9, 1922. Serial No. 535,303.

To all whom it may concern:

Be it known that I, GLENN V. GLADVILLE, a citizen of the United States, residing at Bloomfield, in the county of Greene and State of Indiana, have invented a new and useful Silo Hoop, of which the following is a specification.

This invention relates to silo hoops and to lugs for use in connection therewith, one of the objects of the invention being to provide a means whereby hoops can be placed at regular intervals and close together upon a silo where doors are formed in the walls at regular intervals, the construction of the 10 hoops being such that portions thereof will extend around the door openings so that the doors will in no way interfere with the placing of the hoops and, consequently, the 15 hoops can be arranged closer together than heretofore, thereby insuring a stronger and 20 more rigid silo structure than would otherwise be possible.

A further object is to provide lugs of 25 novel construction for use in connection with the ordinary hoops or rods and which lugs allow for the arrangement of the hoops so that they will extend around a silo in the same horizontal plane with the doors therein, thus giving the same strength as where 30 the same number of hoops are arranged around a silo containing no doors.

A still further object is to provide hoops so constructed that one of them can be placed over every stave unit in the silo.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a front elevation of a portion of a silo having the present improvements combined therewith.

Figure 2 is a section on line 2—2, Figure 1.

Figure 3 is a section on line 3—3, Figure 1.

Referring to the figures by characters of reference 1 designates a silo structure preferably formed of staves and in the structure are provided superposed door openings 2.

Hoops 3 in the form of rods are extended straight around the silo between the doors in the usual manner, the ends of the hoops being connected together by lugs 4 of the usual construction and one of which has been illustrated in Figure 3. Each of these hoops 3 is extended through tie plates 5 located adjacent the upper and lower ends of the door opening 2, the said tie plates being substantially parallel and the hoops being extended through the centers thereof. Each tie plate is provided near its ends with openings 6 and these openings are adapted to receive the intermediate portions of tie rods 7 the ends of which are offset at angles, as shown at 8. The free ends of these tie rods 7 are screw threaded and are extended through angular lugs 9, there being openings 10 in the end portions of these lugs for the reception of the tie rods. Said tie rods can be secured in place in any suitable manner, as by means of nuts 11. The tie rods 7 are arranged above and below the door openings and the ends 8 thereof are adapted to converge towards the lugs 9, these lugs being located beyond the sides of the door openings. A hoop 12 in the form of a rod is extended partly around the silo and has its ends screw threaded and extending through the centers of the lugs 9 at opposite sides of one of the door openings 2. The ends of this hoop are engaged by nuts 13 which serve to draw the hoop tightly about the silo and to pull through the rods 9 and their offset portions 8 upon the tie plates 5.

Lugs 9 are located adjacent opposite sides of each door opening and the tie rods extending therefrom are arranged above and below the door opening. A similar arrangement is provided for each of these openings and one hoop is connected to each pair of lugs 9. Each hoop 3 is connected to the tie rod 7 above and below it by the tie plate 5 mounted on said hoop and thus it will be seen that when the nuts 11 and 13 are tightened the hoops 12 will be drawn taut about the silo and will hold it together securely in horizontal planes intersecting the door openings 2 where it has heretofore been impossible to provide hoops.

Attention is called to the fact that this arrangement of hoops close together is permissible in the present instance without the use of heavy and expensive frames extending around the door openings. Consequently

the cost of construction of a silo provided with hoops such as described in the present case is materially reduced without, however, reducing the efficiency of the silo.

5 What is claimed is:—

1. In a silo structure superposed tie rods arranged in pairs, the ends of the rods of each pair converging, tie plates connecting the tie rods of adjoining pairs, lugs connecting the converging ends of the rods of each pair, and a hoop secured at its ends to the lugs of each pair.
2. In a silo structure the combination with superposed hoops for extending continuously around a silo, and tie plates mounted on each hoop, of tie rods arranged in pairs and extending through the tie plates, the ends of the tie rods of each pair converging, lugs adjustably connected to the converging 20 ends of the tie rods of each pair for holding

said ends together, and hoops interposed between the first mentioned hoops and adjustably fastened at their ends to the lugs.

3. In a silo structure the combination with opposed lugs, said lugs being arranged in superposed pairs, of hoops each having its ends adjustably secured to the lugs of one pair, tie rods connecting the lugs of each pair, and means connecting the tie rods of adjoining pairs for holding the tie rods of each pair spread apart at intermediate points.

In testimony that I claim the foregoing as my own, I have hereto affixed my signature in the presence of two witnesses.

GLENN V. GLADVILLE.
